UNITED STATES PATENT OFFICE.

ISAAC M. HAIR, OF SPARTANBURG, SOUTH CAROLINA.

ARTIFICIAL TOOTH.

1,333,804.

Specification of Letters Patent. Patented Mar. 16, 1920.

Application filed October 3, 1919. Serial No. 328,152.

To all whom it may concern:

Be it known that I, ISAAC M. HAIR, a citizen of the United States, and a resident of Spartanburg, in the county of Spartanburg and State of South Carolina, have made certain new and useful Improvements in Artificial Teeth, of which the following is a specification.

My present invention relates generally to 10 artificial teeth and more particularly to novel effective means for securing the teeth facings in connection with backing members for use principally in bridge work.

It is a well known fact that means now 15 employed and in general use for the purpose of securing tooth facings in connection with backings, while capable of effective employment with relatively thick heavy facings, become ineffective and insufficient for the desired purposes in connection with thin facings, *i. e.*, where it is necessary to grind the facings thin to properly fit them in relation to other teeth.

It has been proposed to bore tooth facings 20 for the reception of pins carried by backing plates, the pins being cemented in the tooth bores and this method is now commonly employed and has been found insufficient under the circumstances above mentioned.

My invention aims at the provision of an 25 active lock coöperating with the tooth facings and one or more pins cemented therein, the locking element itself being cemented in place so that a strong permanent union is effected even where the tooth facing is so 30 thin as to render the usual connection, or a connection without a lock, ineffective.

With the above in mind, my present invention can be better understood from the 35 following detailed description, reference being made to the accompanying drawing, which forms a part of this specification and in which:

Figure 1 is a side view of an artificial 40 tooth showing the practical application of my invention,

Fig. 2 is a sectional view through the tooth prepared for association with its back- 45 ing,

Fig. 3 is a rear elevation of the tooth and backing as seen in Fig. 1,

Fig. 4 is a detailed perspective view of a

tooth backing constructed in accordance with my invention, and

Fig. 5 is a detailed perspective view of 55 the locking pin provided by my invention.

Referring now to these figures, my invention proposes the provision, in artificial teeth, of which one is indicated at 10 in Figs. 1, 2 and 3, of bores, preferably includ- 60 ing a bore 11 which upstands into the material of the artificial tooth at right angles to its base or lower surface 12 and the upper end of which is intersected by a horizontal bore 13 at whose outer end is a conical 65 counter bore 14.

The tooth may also have the bore 15 up- 70 standing therein at a forwardly inclined angle, bores 11 and 15 respectively receiving upright pins 16 and 17 of a tooth back- 75 ing plate 19, or a bridge plate 20. Of these pins 16 and 17 which in practice are pressed upwardly into the tooth bores and into cement, the pin 16 has an upper transverse opening 21, which is adapted to line with the 80 horizontal bore 13 of the tooth for the re- ception of a locking pin 22 shown in detail in Fig. 5, this pin being finally cemented in the bore 13 after the parts are properly fitted, and having an enlarged head 23 at one 85 end which is cemented in the counter bore 14 and subsequently ground flush and bur- nished even with the surface of the tooth.

By a comparison of either Figs. 1 and 2, 90 with Fig. 3, it will be noted that the hori- 85 zontal bore 13 is extended inwardly from the rear of the tooth facing so that in the final secured position, the locking pin 22 will be entirely concealed from view and protected from injury and displacement.

It has been found that the simple use of one or both of the upright bores and with pins cemented therein, is insufficient particu- 95 larly in case it becomes necessary for fitting purposes that the tooth facing be ground very thin. It is obvious in this case, that the pins would have to be cut down in length, and without a positive lock they would and do loosen very readily. With my improved locking pin and extra bore, however, one of the pins, no matter how short they may be, is effectively engaged and held in a permanent manner and by a means, the size and effectiveness of which are not diminished in any

way through cutting down in the height of the tooth.

I claim:—

1. An artificial tooth including a backing 5 having a projecting pin, a facing having a bore to receive the said pin and provided with a second bore remote from the backing at an angle to and intersecting, the first bore and a locking pin in the second bore to engage the backing pin in the first bore, and 10 securely hold the same against displacement.

2. An artificial tooth including a backing, having a projecting pin, a facing having a bore to receive the said pin and provided 15 with a second bore at an angle thereto and intersecting the first bore, located in spaced, approximately parallel relation to the backing and a locking pin in the second bore to engage the backing pin in the first bore, and 20 securely hold the same against displacement, said pins being cemented in their respective bores, as described.

3. An artificial tooth including a backing having pins projecting therefrom at different angles, a facing having bores extending therein at angles corresponding to the said 25 backing pins and adapted to receive the latter, said facing also having a bore opening through its side remote from the backing 30 and arranged at an angle to and intersecting one of its first mentioned bores, one of said pins in one of the intersecting bores having an opening positioned to register with the last mentioned bore of the tooth and a locking pin secured in the last mentioned bore of the tooth, and extending through the open- 35

ing of the last mentioned backing pin, as described.

4. An artificial tooth including a backing, having a pin projecting therefrom, a facing 40 having one surface for engagement of the backing plate and having a bore extending inwardly from said face to receive the backing pin, said facing being provided with a second bore at an angle to and intersecting 45 its first bore and opening through another surface of the facing remote from the backing, said backing pin having an opening positioned to register with the second bore, and a locking pin secured within the second bore 50 of the facing and extending through the opening of the backing pin.

5. An artificial tooth including a backing, having a pin projecting therefrom, a facing 55 having one surface for engagement of the backing plate and having a bore extending inwardly from said face to receive the backing pin, said facing being provided with a second bore at an angle to and intersecting 60 its first bore and opening through another surface of the facing remote from the backing, said backing pin having an opening positioned to register with the second bore, and a locking pin secured within the second bore 65 of the facing and extending through the opening of the backing pin, said second bore of said facing having a counter bore at its outer end and said locking pin having an enlarged head at one end secured within the counter bore flush with the adjacent tooth 70 surface, as described.

ISAAC M. HAIR.
